COMBINATION KEY HOLDER AND TENSION MEMBER FOR TOY CASH REGISTERS

Henry A. Kroenlein, Los Angeles, Calif., assignor to Ruth P. Berry, Jackson, Mich.

Application January 10, 1947, Serial No. 721,192

3 Claims. (Cl. 235—12)

1

The present invention relates to improvements in toy cash registers of the type and construction as disclosed in United States Letters Patent No. 1,906,361.

An object of the present invention is to provide an improved combination key lever retaining and tensioning member for toy cash registers of the type and construction disclosed in the aforesaid patent.

Another object is to provide a key lever holding and tensioning structure for toy cash registers of the type described which facilitates assembly and reduces the cost of production.

Other objects and advantages residing in the specific construction, and the combination and arrangement of component parts will be more fully understood from a consideration of the following specification and appended claims.

In the drawings,

Fig. I is a vertical, cross-sectional view of the toy cash register,

Fig. II is a fragmentary enlarged view of a portion of the vertical cross-section, shown in Fig. I,

Fig. III is a perspective view of the key retaining and tensioning member removed from the assembly, and

Fig. IV is an elevational view of the cross plate stamping in which the key levers are fulcrumed.

The toy cash register casing 10 comprises end walls 12, a base 14, an arcuate front wall portion 16, and a target viewing portion 18.

Extending between and supported by the end walls 12 is a sub-frame comprising a sheet metal base 20 having end flanges 22 which may be spot-welded to the end walls 12. A turned-up flange 24 at the rear edge of the base 20 is provided with equally spaced slots 26 to receive and guide the target actuating ends 28 of the key levers 30. The levers 30 are swingable and operate in vertical slots 32 formed through the arcuate front 16 of the case structure of the toy cash register. Each key lever 30 is notched out at 34, in its middle portion on the under side or edge, to provide a pivot point. Slots 36 are provided in a vertically disposed plate member 38, which extends transversely between the casing end walls 12 and forms part of a sub-frame, this plate member 38 having a base flange 40 by which it is connected to the base 20 and having also end flanges 38a by which the plate member is secured to the casing end walls 12. The slots 36 which serve as bearing and spacing slots for the several key levers, are aligned with the slot 32, and these slots 32 and 36 space and guide the key levers 30 in their mount-

ing and operation. By fitting the key levers through the aligned slots 32 and 36, with the respective notches 34 resting within the slots 36, the key levers are loosely mounted and are fulcrumed in the slots 36 for free swinging movement. Keys 42 are mounted on the outer ends of the key levers 30 projecting outside of the casing front wall portion 16, and are thus freely accessible to the user.

A combination key lever retaining and tensioning member comprises a sheet metal flap plate 44 having a rib 46 along one edge and a turned flange 48 along the opposite edge. This flap plate 44 is swingably mounted in connection with the vertically disposed plate member 38 substantially as shown by the full lines and dotted lines in Fig. III, and the dotted lines in Fig. IV of the drawing. To this end, the flap plate has slots 50 in the ends thereof received through the opening 51 in the cross-plate 38. Bearing shoulders are provided at 51a, at each end of the opening 51, with bearing flanges 51b immediately thereabove.

In assembling the parts, the flap plate 44 has the flanged edge 48 thereof inserted through the opening 51, and the bearing slots 50 then receive the bearing flanges 51b and this flap plate is supported for rocking or swinging movement upon the bearing shoulders 51a. With this mounting and association of the parts, the flap plate 44 can be readily fitted in place, after all of the several key levers 30 have been positioned through the slots 32 and 36, and when plate 44 rests against the bearing shoulders 51a the plate is swingably mounted with the rib portion 46 resting upon and extending transversely across all of the key levers.

An arcuate spring 52 supported between the cross-plate 38 and the inner swinging portion of flap plate 44 serves to tension the flap plate into the position shown in full lines in Figs. I, II, and III, with the flange 48 abutting the horizontal portion 53 of the plate 38, as a stop.

As will be readily apparent, with the parts mounted in the manner set forth, depressing any one of the keys 42 will cause its associated key lever member 30 to pivot or swinging about its fulcrum, and while the flap plate will prevent displacement of any key lever from its fulcrum mounting, pressure exerted upon any key will cause the associated key lever to pivot the flap plate 44 around its swinging mounting, and against the tension of the spring 52.

The targets 54, selectively raised by the levers 30, have upper indicating portions 56 and lower portions 58 engaged by the ends 28 of levers 30. Intermediate the ends of the targets 54 are turned

out flanges 69 provided with notched portions 62. Vertically aligned slots in the members 64 and 66 provide vertical guiding support to the targets 54.

Hinged at 68 along the outer edge of the portion 64 is a latch plate 70, urged toward the targets 54 by a spring 72. When a target 54 is selectively raised by the lever 30, the latch plate 70 engages into the notch 62 of the elevated target 54 in a manner indicated in dotted outline in Fig. I. Through this means the indicating portion 56 of 10 the selected target 54 is thus held in position to be viewed through the opening 74.

To release the latch member 70 from the notch 62 of the selected target 54, upon depressing a different key 42, the rear edge of the plate 44 engages a target releasing member 76 which fulcrums around an edge of the slot 78. The engagement between the member 44 and the portion 80 of the member 76 results in the portion 82 engaging with a tab 84 of the latch 70 to hinge the latter out of the engagement with the notch 62 of the elevated target 54 in the manner illustrated in Fig. II. The timing of the structure is such that the elevated target 54 is released through the movement of the latch 70 from the full line to dotted line position as shown in Fig. II, yet the latch 70 is returned by the spring 72 to a position to engage with the notch 62 of the newly selected target 54.

If a comparison is made between the structure shown in the aforesaid patent for tensioning the key levers and the present disclosure, it will be observed that in lieu of a plurality of springs, one for each key, the single spring 52 functions to tension all of the levers 30 through the flap plate 44. It will be further appreciated that this flap plate member 44 is so mounted with respect to the pivotal points 36 that it functions not only to tension all the key levers to their normal non-depressed positions but also to hold the key levers located in the open ended slots 36 since as is clearly seen in Figs. I and II, the flap plate is mounted in close superposed relationship to the key levers and overlies their pivot points 34, with portions of the flap plate extending beyond opposite sides of the cross plate 38. The modified and improved construction thereby involved materially facilitates assembly and considerably reduces the manufacturing costs while at the same time a more uniform operation of the key levers is obtainable.

Having thus described my invention, what I claim as new and desire to cover by Letters Patent is:

1. In a toy cash register, supporting structure, a plurality of key levers, each of said levers having a fulcrum point intermediate its ends, a fulcrum on the supporting structure on which said key levers are loosely disposed in a transversely spaced assembly for rocking movement upon their fulcrum points to and from depressed positions, and an elongated flap plate swingably mounted across the key lever assembly, said flap plate having its hinge mounting above and in proximity to the fulcrum mounting of the several key levers to retain said levers on said fulcrum mounting and having its swinging edge engageable with the inner swingable portions of the key levers for maintaining said levers in nondepressed position.

2. In a machine according to claim 1, spring means for tensioning said swinging edge into engagement with the inner swingable portions of the key levers.

3. In a toy cash register, supporting structure, a plurality of key levers, each of said levers having a fulcrum point intermediate its ends, a fulcrum on the supporting structure on which said key levers are loosely disposed in a transversely spaced assembly for rocking movement around their fulcrum points to and from depressed positions, an elongated flap plate having bearing slots at its hinged edge, flange-like parts carried by 20 the supporting structure and having bearing portions received in the slots of the plate, said bearing flange portions being disposed to swingably mount the flap plate above and in proximity to the fulcrum mounting of the several key levers 25 to retain said levers on said fulcrum mountings and the flap plate having its swinging edge engageable with the inner swingable portions of the key levers for maintaining said levers in undepressed relation, and spring means tensioning 30 said plate into the key lever contacting relation.

HENRY A. KROENLEIN.
